UNITED STATES PATENT OFFICE.

WILLIAM J. VICTORY, OF NEW BRITAIN, CONNECTICUT, ASSIGNOR TO NEW BRITAIN MACHINE COMPANY, OF NEW BRITAIN, CONNECTICUT, A CORPORATION OF CONNECTICUT.

SPEED-HANDLE WRENCH EXTENSION.

Application filed January 17, 1925. Serial No. 3,063.

This invention relates to a speed handle wrench extension and among the objects of the invention are the provision of an article of the character set forth which is simple 5 in construction and which is quite effective in action.

In the drawing accompanying and forming part of the present specification, there is represented in detail a form of embodiment 10 of the invention which, to enable those skilled in the art to practice the same, will be set forth fully in the following description. I am not restricted to this exact disclosure. I may depart therefrom in a number 15 of respects within the scope of the invention defined by the claim succeeding such description.

Referring to said drawing:

Fig. 1 is an elevation of a wrench extension involving the invention, the view also illustrating an element of the wrench at the right.

Fig. 2 is a sectional elevation of the upper part of the wrench extension with the handle in cross section.

Fig. 3 is a cross section on the line 3—3 of Fig. 1 looking toward the right.

Fig. 4 is a longitudinal section.

Like characters refer to like parts 30 throughout the several views.

As shown, the wrench extension comprises a bowed member 2, having a crank handle portion 3 near one end and a shank 4 near the other end, upon which is suitably mounted 35 for free rotation a head 8, which may be locked thereto in any suitable manner, as by a spring ring 6 located within complementary grooved portions of the shank and the lower end 7 of the handle. One of the 40 grooves is shown at 5 (Fig. 2). At the lower end of the crank handle portion 3 is a right angled extension 9, to which is secured a socket 10, the end of which terminates short of a line coincident with the axis of the shank 4. The outer end of the 45 socket 10 is provided with an angular opening designed to receive the angular end 13 of a wrench bar 14, which end 13 may be provided with a spring pressed detent 16, to 50 frictionally hold the bar 14 in the socket.

The length of the part 13 is such that the axis of the bar 14 will be substantially coincident with the axis of the shank 4 when the parts are assembled. 15 is a socket wrench head, which has a cavity in one end 55 designed to receive a polygonal nut or bolt head, while at the other end it has an opening designed to receive the polygonal end of the rod 14. 18 is a groove or notch, which is designed to receive the spring detent 16, to frictionally secure the wrench bar to the wrench head. It will be observed that when the parts are thus assembled, as shown in the vertical position in Fig. 1, the tool may be grasped in the hand when resting on the head 8, the other hand grasping the crank 3, whereupon the wrench bar 14 may be rapidly rotated, to correspondingly rotate the socket wrench head 15. By this arrangement the socket wrench bar 14 may 60 be utilized in connection with the speed handle, or it may be detached therefrom and used as indicated in the right-hand side of Fig. 1. The socket 10 is preferably attached to the extension 9 by means of the pin 11, 65 and the inside of the cavity for receiving the wrench bar extension 13 may be recessed, as at 17, for receiving the detent 16. It will be observed that when the parts are assembled the main body 14 of the bar is held in 70 substantial alignment with the shank 4 of the speed handle.

What I claim is:

In a device of the class described, a bowed member comprising a shank, an offset crank 85 handle, a right angled extension, and a socket terminating short of a line coincident with the axis of the shank, a co-operating right angled wrench bar having a long arm and a short arm, both ends of said bar 90 being of corresponding angular cross section, said socket having an angular aperture to receive either end of said wrench bar, the length of the short arm of said bar being such as to position the long arm in substantial alignment with the shank of the bowed member when the end of said short arm is seated in said socket.

In testimony whereof I affix my signature.

WILLIAM J. VICTORY.
